UNITED STATES PATENT OFFICE.

SAMUEL B. WHITE, OF GEORGETOWN, OHIO.

ATTACHMENT FOR AUTOMOBILES.

1,115,356.

Specification of Letters Patent. Patented Oct. 27, 1914.

Application filed December 30, 1912. Serial No. 739,173.

To all whom it may concern:

Be it known that I, SAMUEL B. WHITE, a citizen of the United States, residing at Georgetown, in the county of Brown and 5 State of Ohio, have invented certain new and useful Improvements in Attachments for Automobiles, of which the following is a specification, reference being had therein to the accompanying drawing.

10 This invention relates to attachments for automobiles. In the operation of motor driven vehicles it frequently happens that the vehicle becomes stalled because of the slipping of the driving wheels on the road- 15 way. This slipping is due either to a soft, slippery roadway or to a steep inclination as, for example, a bank along the side of the roadway. It has been proposed to start the vehicle and move it to a part of the road 20 where the drive wheels will take hold by mounting a drum on one of the drive wheels, attaching one end of a cable to the drum and carrying the other end of the cable to a point in advance of the drive wheel and 25 securing the same to a fixed object, such as a stake driven into the ground or a post along the side of the road. Then when the drive wheels are rotated the cable will be wound upon the drum and the vehicle moved 30 forward. Such a drum cannot well be at- tached permanently to the wheel because it projects too far beyond the same and in de- 35 vices heretofore proposed the means for at- taching the drum to the wheel has been cum- bersome and difficult of attachment, requir- 40 ing in many, if not in all, instances the use of tools or implements.

The object of the present invention is to 45 provide a device of this character which can be readily attached to and detached from the traction wheel and this without the use of tools or implements of any kind; further, to construct and arrange the attachment de- 50 vices in such a manner that the connection between the drum and the wheel will be a strong, durable one; and to so arrange the several parts that the drum will be well braced and have ample strength for its work.

In the accompanying drawings, Figure 1 55 is a plan view of a portion of an automobile showing the drum attached to the driving wheel and in operative position; Fig. 2 is a horizontal sectional view, taken centrally through the drum showing the same at- tached to a wheel; and Fig. 3 is a perspective

view of the drum showing the attaching devices.

In these drawings I have illustrated one embodiment of the invention and have shown the drum at 1 as of the usual form 60 and have attached thereto one end of a cable 2 which may be wound about the drum when the latter is rotated. It will be understood, however, that the drum may be of any suitable construction adapted to take up 65 a flexible pulling member, such as the cable.

In order that the drum may be quickly and easily attached to the spokes of a wheel I have provided the drum with attachment devices which will engage the spokes of a 70 wheel, as indicated at 3, and, when the wheel is rotated, firmly grip the spokes and cause the drum to rotate therewith. In the present instance these attachment de- 75 vices are hook-shaped in form, as indicated at 4, and are four in number. The devices are so arranged upon the drum 1 that they may be inserted between the spokes of the wheel and by giving the drum a short ro- 80 tary movement may be caused to grip the spokes and thus retain the drum firmly in position. As soon as the driving wheel be- 85 gins to rotate the devices will be caused to still more strongly grip the spokes of the wheel and the greater the resistance offered to the rotation of the drum the tighter will be the connection between the same and the wheel.

The drum and attachment devices are so 90 constructed and arranged that the former will be braced against any twisting move- 95 ment and, to this end, the drum is pro- vided with a laterally extending portion or flange 5 to which the hook-shaped at- tachment devices are here shown as rigidly 100 secured. This flange fits tightly against the spokes of the wheel on the outer side there- 105 of, the inner end of the drum being hollow to receive the adjacent end of the hub 6 of the wheel. The shape of the attachment de- 110 vices is such that when these are in en- gagement with the respective spokes the flanged end of the drum will be held snugly against the side of the wheel and the at- tachment devices will prevent the drum 115 from being pulled away from the wheel, as well as cause it to rotate therewith.

The operation of the device will be un- 120 derstood from the foregoing description and it will be apparent that it is only nec-

essary to place the drum in position over the hub with the attachment devices between the spokes of the wheel and give the drum a slight turn to bring the hook-shaped devices into engagement with the respective spokes and firmly attach the drum to the wheel; and that the drum can be removed as readily by rotating the drum far enough to disengage the hook-shaped devices from their spokes. Further, it will be apparent that the construction of the device is such that not only can the drum be attached to and detached from the wheel without the use of implements of any kind but that the construction of the drum and the attachment devices is such that they will not bind or become locked upon the wheel no matter how severe the strain to which they are subjected and, consequently, the drum can be readily removed at the end of any operation.

While I have shown and described one embodiment of my invention it will be understood that this has been chosen for the purpose of illustration only and that I do not desire to be limited to the details of construction shown and described, for ob-

vious modifications will occur to a person skilled in the art.

Having thus fully described my invention, what I claim as new and desire to secure by Letters Patent, is:—

In a device of the character described, a drum having a central recess in one end thereof and fastening devices rigidly secured to said end of said drum at intervals about said recess and comprising short hook-shaped members projecting beyond said end of said drum and adapted to extend between the spokes of a wheel, said hook-shaped members being so constructed and arranged that the rotation of said drum about its longitudinal axis in one direction will cause said hook-shaped members to operatively engage the respective spokes of said wheel and retain the end of said drum into engagement with said wheel.

In testimony whereof, I affix my signature in presence of two witnesses.

SAMUEL B. WHITE.
